DISPENSING CLOSURE

Alex Limbach, Carmel, N. Y.

Application November 3, 1944, Serial No. 561,688

2 Claims. (Cl. 299—88)

This invention relates to an improved one-hand operated dispensing closure for a container of material which it is desired to dispense in dispersed condition.

An object of this invention is a simple and inexpensive dispenser composed of a few parts easy to manufacture and which may be inserted in the neck of a container in the manner of a stopper.

One embodiment of this invention comprises a centrally apertured stopper of suitable configuration to fit into a bottle neck or the like and having a circular flange at one end. The flange has a concave face except for a narrow rim and a flexible strip overlies the flange, the strip being of less width than the diameter of the concave portion and being of proper length and end configuration to conform to said flange. A bulb having an annular ring overlies the flexible strip and an annular band encloses and clamps together the aforementioned members. The band is provided at its inner face with a recess having an aperture leading therefrom through the band to the exterior thereof. A spiral groove in the bulb rim provides communication between the recess and the interior of the bulb above said flexible strip.

Upon compression of the bulb, the flexible member is forced into engagement with the concave surface of the stopper flange to close the aperture against downward flow and the contents of the bulb are discharged through the spiral groove into the recess and from thence through the aperture to atmosphere. Upon expansion of the bulb, the flexible member returns to its original position and liquid is drawn into the bulb through the clearance provided by the straight sides of the flexible strip.

Other objects, novel features and advantages of this invention will become apparent from the following specification and accompanying drawing, wherein:

Fig. 1 is an elevation of a container equipped with a dispenser embodying the invention;

Fig. 2 is a section through the dispenser on the line 2—2 of Fig. 1;

Fig. 3 is a section on the line 3—3 of Fig. 2 looking in the direction of the arrows;

Fig. 4 is a section on the line 3—3 of Fig. 2 looking in the direction opposite to the arrows, and

Fig. 5 is a view similar to Fig. 2 of a modification.

A stopper 10 of rubber or other suitable material is of generally conical configuration and has

an annular flange 11. In the stopper there is provided a central bore 12 leading between the bottom and top faces of the stopper, the latter of which is slightly concave except for a narrow rim portion 13. A tube 12a of glass or other suitable material has one end seated in the bore 12 and the other end extending nearly to the bottom of the container. A strip 14 of flexible material overlies the upper end of the stopper 10 and is of less width than the diameter of the concave portion of the upper face of the stopper. The strip 14 is of proper length and end configuration to conform to the periphery of the flange 11.

15 A substantially semi-spherical bulb 15 of rubber or other suitable material has a flange 16 overlying the strip 14. A band 17 of metal has inwardly directed flanges 18 and 19 engaging the upper surface of the flange 16 and the lower surface of the flange 11 to clamp the bulb to the stopper with the flexible strip 14 interposed between them. The band 17 has an offset portion 20 forming a recess 21 in the inner surface of the band and an aperture 22 leads from the recess 25 to the exterior of the band. A spiral groove 23 is provided in the flange 16 to establish communication between the interior of the bulb 15 and the recess 21.

20 A groove 24 is provided in the conical surface 30 of the stopper 10 and leads from the bottom end thereof up to and partially along the under surfaces of the flange 11. The stopper 10 is inserted in the neck 25 of a suitable container with the upper end of the groove 24 exposed to provide 35 communication between atmosphere and the interior of the container.

Upon compression of the bulb 15, the flexible member 14 is forced into engagement with the concave top surface of the stopper to close the 40 passageway 12 against downward flow and the contents of the bulb are discharged through the groove 23 into the recess 21 and from thence through the aperture to atmosphere. Upon expansion of the bulb 15, the flexible member 14 returns to its original position and liquid is drawn 45 into the bulb by way of the clearance between the sides of the strip 14 and the bulb 15. Due to the fact that the groove 23 is spiral, the stream of liquid and air from the bulb 15 is introduced 50 into the recess 22 in such manner that it is caused to circle around the recess periphery before escaping through the aperture 22, thereby insuring thorough mixture of the air and liquid in dispersed condition.

In Fig. 5, 30 designates the threaded neck of

a bottle or similar container on the end of which rests a disk 31 of rubber or other suitable material having a central bore 32 extending between the bottom and top face of the disk 31, the latter of which is slightly concave except for a narrow rim portion 33. A strip 34 of flexible material overlies the upper face of the disk 31 and is of less width than the diameter of the concave portion of the upper face of the disk. The strip is of proper length and end configuration to conform to the periphery of the flange 11.

A semi-spherical bulb 35 of rubber or other suitable material has a flange 36 overlying the strip 34. A band 37 of metal has an inwardly directed flange 38 engaging the upper surface of the bulb flange 36 and is provided with a threaded portion 38a screwed onto the bottle neck 30 to clamp in assembled relation the bottle, the disk 31, the flexible member 34 and the bulb 35. A tube 39 of glass or other suitable material has its upper end fitting into the bore 32 and its lower end extending nearly to the bottom of the container 30.

The band 37 has an offset portion 40 forming a recess 41 in the inner surface of the band and an aperture 42 leads from the recess to the exterior of the band. A spiral groove 43 is provided in the face of the flange 36 to establish communication between the interior of the bulb 35 and the recess 41.

Operation of the modification illustrated in Fig. 5 is the same as that of the modification illustrated in the remaining figures and will not be repeated in detail. Alternate compression and expansion of the bulb 35 serves to dispense a mixture of air and liquid through the aperture 42 in dispersed condition. Atmospheric pressure is maintained within the container by leakage along the threaded connection between the band 37 and the container neck 30 and for this purpose the band may be unscrewed slightly.

I claim:

1. A dispensing device comprising a centrally apertured stopper adapted to fit into a bottle neck or the like and having a circular flange at one end, said stopper having a concave face at its flange end, a flexible strip overlying said flange, said strip being of less width than the diameter of the concave portion and being of proper length and end configuration to conform to said flange, a bulb having an annular rim overlying said flexible strip, an annular band enclosing and clamping together the aforementioned members, a recess in said band with an aperture leading therefrom through the band to the exterior thereof, and a spiral groove in the bulb rim having one end communicating with said recess and the other end communicating with the interior of said bulb above said flexible strip.

2. A dispensing device comprising a centrally apertured circular member adapted to engage the end of a bottle neck or the like and having a concave face, a flexible strip overlying said member, said strip being of less width than the diameter of the concave portion and of proper length and end configuration to conform to the periphery of said member, a bulb having an annular rim overlying said flexible strip, an annular band enclosing the aforementioned member and having an inwardly directed portion overlying the bulb rim, said band also having a threaded connection with said container neck to clamp the circular member against the end of the bottle neck, a recess in said band with an aperture leading from the band to the exterior thereof, and a spiral groove in the bulb rim having one end communicating with said recess and the other end communicating with the interior of said bulb above said flexible strip.

ALEX LIMBACH.
